(57) **CLAIM**

The ornamental design for “dual seat pedestal conversion for a single seat pedestal receptacle,” as shown and described.

DESCRIPTION

FIG. 1 is a perspective view of the dual seat pedestal conversion for a single seat pedestal receptacle showing my new design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom view thereof.
